United States Patent

Des. 236,556
Patented Aug. 26, 1975

236,556

CARRYING CASE FOR COLORISTS MATERIALS OR THE LIKE

Albert E. Di Paola, Fishers and Louis C. Sandstrom,
Fairport, N.Y., assignors to Xerox Corporation, Stamford, Conn.

Filed Oct. 15, 1973, Ser. No. 406,772

Term of patent 14 years

Int. Cl. D3—02

U.S. Cl. D87—3 R

FIG. 1

FIG. 1 is a front, bottom and right side perspective view of a carrying case for colorists materials or the like showing our new design;

FIG. 2 is a front elevational view;

FIG. 3 is a right side elevational view; and

FIG. 4 is a front perspective view in opened condition.

We claim:

The ornamental design for a carrying case for colorists materials or the like, substantially as shown and described.
